(57) **CLAIM**

I claim the ornamental design for a portion of a shell of a sports helmet, as shown and described.

DESCRIPTION

FIG. 1 is a top, front and left side perspective view of a portion of a shell of a sports helmet showing my new design; FIG. 2 is a rear and left side perspective view thereof; FIG. 3 is a right side view thereof; and, FIG. 4 is a top plan view thereof.

The environmental structure shown in broken lines forms no part of the claimed design.
